US00D978081S

(12) **United States Design Patent** (10) **Patent No.:** **US D978,081 S**
Kuhn et al. (45) **Date of Patent:** **** Feb. 14, 2023**

(54) **ENCLOSURE**

- (71) Applicant: **SUNPOWER CORPORATION**, San Jose, CA (US)
- (72) Inventors: **Brian Kuhn**, Austin, TX (US); **William J. Morris**, Round Rock, TX (US); **Daidipya J. Patwa**, San Francisco, CA (US); **Sandeep Narla**, Newark, CA (US)

- (73) Assignee: **Sunpower Corporation**, San Jose, CA (US)

(**) Term: **15 Years**(21) Appl. No.: **29/768,274**(22) Filed: **Jan. 28, 2021****Related U.S. Application Data**

- (63) Continuation of application No. 29/706,559, filed on Sep. 20, 2019, now Pat. No. Des. 909,974.
- (51) **LOC (14) Cl.** **13-03**
- (52) **U.S. Cl.**
USPC **D13/122**
- (58) **Field of Classification Search**

CLAIM

The ornamental design for an enclosure, as shown and described.

DESCRIPTION

FIG. 1 is a top front perspective view of an enclosure showing the claimed design;

FIG. 2 is a top rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the enclosure that form no part of the claimed design.
